METHOD OF MAKING ELECTRICAL SOCKET CONNECTIONS

Edward A. Sprigg, Toledo, Ohio, assignor to H. H. Buggie & Company, Toledo, Ohio, a corporation of Ohio

Application January 22, 1945, Serial No. 573,853

2 Claims. (Cl. 29—155.55)

1

This invention refers to electrical connectors and to a method of producing the socket contact part for electrical connectors.

One of the principal objects of this invention is to provide an electrical contact socket which lends itself to high production processing at a reasonable cost and which yieldably grips a cooperating contact pin in a manner to reduce the potential drop to a minimum.

Another object of this invention is to provide a method of manufacturing the socket composed of a relatively few simple steps capable of being expediently and inexpensively carried out.

A further object of this invention is to provide a spring metal socket having axially spaced continuous annular portions and having the portion intermediate the annular portions diagonally slotted and twisted to reduce the internal diameter of the bore in the socket sufficiently to enable the intermediate portion of the socket to grip a cooperating contact pin.

The foregoing as well as other objects will be made more apparent as this description proceeds, especially when considered in connection with the accompanying drawing, wherein:

Figure 1 is an enlarged side elevation of a socket electrical contactor constructed in accordance with this invention;

Figure 2 is an enlarged cross-sectional view taken on the line 2—2 of Figure 1; and

Figure 3 is an enlarged fragmentary longitudinal sectional view through the socket shown in Figure 1.

The electrical contact socket is illustrated in the several figures of the drawing by the reference character 10 and is preferably formed of spring metal having good electrical conducting characteristics such, for example, as spring brass. The contactor 10 comprises an electrical cable connecting end portion 11 and a socket portion 12 axially bored to receive a cooperating contactor pin (not shown).

The socket portion 12 is provided with axially spaced continuous annular portions 13 and with an intermediate portion 14 having slots 15 formed in opposite side walls. The slots 15 extend from one annular portion 13 to the other annular portion and are respectively disposed in planes which cross or extend in diagonal relation to each other. The planes intersect one another in a plane including the axis of the bore in the socket at a point midway between the continuous annular portions 13, as clearly shown in Figure 2 of the drawing.

In actual practice, the bore in the socket is drilled or otherwise formed with an internal di-

2

ameter slightly greater than the external diameter of the contact pin to be ultimately engaged in the bore. The opposite side walls of the intermediate portion are then sawed or otherwise cut to form the narrow diagonal slots 15 therethrough. Owing to the relative positions of the slots 15 previously described, it will be noted that they, in effect, divide the intermediate portion 14 of the socket contact into spaced generally spiral shaped sections integrally connected at opposite ends by the continuous annular portions 13.

Upon completion of the sawing or cutting operation, the contact 10 is clamped in a jig or other suitable holding fixture and the socket end is twisted or turned. The slots 15 are thereby partially or completely closed and the internal diameter of the socket or bore is reduced. In order to avoid deformation of the cylindrical bore during the twisting operation, a suitable mandrel (not shown) having an external diameter somewhat less than the corresponding diameter of the contact pin to be ultimately engaged in the socket is inserted in the bore prior to twisting or turning the socket. In any event, the width of the slots is predetermined to enable the twisting movement required to set the metal of the intermediate portion 14 to an internal diameter slightly less than the external diameter of the pin to be engaged in the socket or bore. The construction is such that insertion of the appropriate contact pin into the socket imparts a spiral expanding motion to the intermediate portion 14 of the socket within the elastic limits of the metal so that the pin is firmly gripped by the socket.

What I claim as my invention is:

1. The method of making a spring metal electrical socket connector having a bore comprising cutting opposite sides of the socket to form slots extending in planes diagonally disposed with respect to each other, reducing the internal diameter of the bore by turning one end of the slotted portion of the socket relative to the opposite end and predetermined the width of the slots to enable setting the metal of the socket portion to the reduced internal diameter aforesaid.

2. The method of making a spring metal electrical connector socket comprising forming a bore in the socket having a diameter somewhat greater than the external diameter of the contact pin to be engaged in the socket, cutting opposite sides of the socket to form slots extending in planes diagonally disposed with respect to each other, and reducing the internal diameter of the bore by twisting the slotted portion of the socket be-

yond the elastic limit of the metal to set the metal to said reduced diameter.

EDWARD A. SPRIGG.
